UNITED STATES PATENT OFFICE

2,095,445

RETURN BEND

Frederick E. Key, St. Louis, Mo., assignor to Key Company, East St. Louis, Ill., a corporation of Missouri

Application March 8, 1935, Serial No. 9,926

5 Claims. (Cl. 285—20)

This invention relates to return bends forming connections between the ends of tubes in oil stills which are subjected to high temperatures and high pressures.

5 In one aspect, the present invention comprises certain additions and improvements in the type of return bends disclosed in my prior Patent No. 1,987,300, January 8, 1935, and an object of the invention is to provide improved means for connecting the housing sections to permit relative longitudinal adjustment thereof and, at the same time, maintaining leak-proof joints between the ends of the return bend and the housing sections. The improved connection between the housing sections permits certain limited lateral and longitudinal adjustments of said sections as required to maintain leak-proof joints with the return bend and said connection also prevents the housing sections from twisting or turning relatively.

20 Another object of the invention is to provide improved means for holding the housing sections in proper connection with the tubes.

Another object of the invention is to provide a return bend embodying novel features whereby the return bend may be conveniently detached or pulled from the housing sections.

Other objects of the invention will be apparent from the following description, reference being made to the annexed drawings, in which—

30 Fig. 1 is an end elevation of a preferred form of the invention.

Fig. 2 is a cross sectional view on the line 2—2 of Fig. 3.

Fig. 3 is a sectional view of the return bend and housing sections mounted in connection with the ends of tubes.

Fig. 4 is a view approximately on the line 4—4 of Fig. 3.

Fig. 5 is a relatively enlarged view, partly in section, showing alternative means for holding the housing sections in connection with the tubes.

Fig. 6 is a similar view showing another variation in the means for holding the housing sections in connection with the tubes.

45 Fig. 7 is an inner side elevation of the annular portion of one of the housing sections showing the structure for preventing the housing sections from twisting or turning relatively.

Fig. 8 is an end elevation showing equipment for withdrawing or pulling out the return bend from the housing section.

Fig. 9 is a side elevation of the structure shown in Fig. 8.

Fig. 10 is an elevation looking toward one of the side edges of Fig. 9.

As shown in Figs. 1 to 4, inclusive, each housing section comprises an annular portion 1 having an opening in which grooves 2 are formed. The ends of the tubes 3 and 4 extend into the openings in the respective housing members and are rolled or expanded into the grooves 2, thereby rigidly attaching the housing sections to the ends of the tubes. The outer end of the opening through each annular portion 1 has an inwardly tapered smoothly ground wall 5. The tapered ends 6 of the return bend 7 are smoothly ground and extend into the tapered portions of the openings through the housing members and the tapered walls on the ends of the U-bend seat closely against the walls 5 and form a leak-proof joint. 5 The ends of the return bend are separated from the ends of the tubes by spaces 8 which are crossed by tubular liner members 9 extending into enlarged portions in the ends of the tubes and the return bend, respectively. The inside 10 diameter of the liners 9 is the same as the inside diameter of the tubes and the return bend. The liner members 9 cooperate with the tubes and the return bend to form leak-proof joints. 15

Each housing member comprises a pair of outwardly extended arms or walls 10 having holes 11

near their outer ends. Each of the holes 11 has an outwardly inclined wall 12 adapted to be engaged by inclined walls 13 formed on the toggles 14.

Each toggle 14 is formed with a threaded hole through which a set screw 15 is screwed into engagement with a shoulder 16 on the return bend 7. The set screws 15 are approximately in axial alignment with the tubes 3 and 4, respectively,

and function to force the ends of the return bend 7 into the housing members and to hold the parts in such adjustment to maintain a leak-proof joint. 20

The toggles 14, having their inclined walls 13 engaging the inclined walls 12 on the arms or walls 10, prevent said arms or walls 10 from spreading when the screws 15 are tightened and when the device is in service and subjected to high pressure and high heat. To facilitate assem-

bling the toggles 14, one end of each toggle is provided with a rounded wall 17, so that when the opposite end of the toggle is passed through the hole 11 in one of the arms or walls 10, the rounded portion 17 on the opposite end of the toggle

will permit said opposite end to move inwardly between the arms or walls 10 and be inserted in the hole 11 and properly assembled. 40

The annular portion 1 of each housing member has a part 18 extending toward the other

housing member. Each part 18 has therein a groove 19 receiving a key 20 on the opposite

housing section. In the manufacture of the device, each housing section may be formed with two parallel grooves 19 and the key 20 may be placed in one of said grooves and welded or otherwise rigidly secured therein. As shown, the keys 20 are rectangular in cross section and are provided with round outwardly extended threaded ends 21.

The outer ends of the portions 18 have complementary transverse notches 22 cooperating to form a groove in which a plate 23 is seated. The plate 23 has holes 24 through which the keys 20 extend and the threaded ends 21 of said keys are beyond the plate 23. A nut 25 is screwed on the threaded end 21 of each key 20 and is separated from the plate 23 by a space 26, which arrangement permits limited relative longitudinal movement and adjustment of the housing members 1. The holes 24 are of greater transverse width than the keys 20 (Fig. 2), so that it is possible for the housing members 1 to move toward and from each other to a limited extent, as required to obtain leak-proof joints when the parts of the return bend are assembled.

In the construction shown in Fig. 5, the annular portion 1 of the housing member does not directly engage the tube but has a shoulder 27 engaging a circumferential shoulder 28 on a collar 29 having internal grooves 30 into which the end of the tube is rolled or expanded. The tapered ends 6 of the return bend 7 telescope into the outer ends of the collars 29 and seat against smoothly ground tapered walls 31, corresponding to the tapered walls 5, and thereby maintain a leak-proof joint. The remaining elements of the structure shown in Fig. 5 are the same as the elements already described and like reference numerals are applied thereto.

In the arrangement shown in Fig. 6, the annular portion 1 of the housing member has an internal flange 32 engaging against the inner end of a collar 33. The end of the tube is rolled or expanded into a groove 34 in the flange 32 and also into a groove 35 in the collar 33. The tapered ends 6 of the return bend extend into tapered openings in the outer ends of the collar 33 and seat against smoothly ground walls 36 to maintain a leak-proof joint.

The remaining features shown in Fig. 6 are the same as the features shown in Figs. 1 to 4, inclusive, and like reference numerals are applied to like parts.

A pair of spaced outwardly extended lugs 37 are formed integral with each end of the return bend 7 and provided with notches 38 in their lower edges. The devices used to withdraw or pull out the return bend 7 from the housing members for the purpose of opening the tubes so that the tubes may be cleaned or for other purposes may be engaged with these lugs 37 and operated to detach the return bends. Appropriate devices for use in detaching the return bends are shown in Figs. 8, 9 and 10. Said devices comprise a plate 39 adapted to be seated on the ends 55 of the arms or walls 10 and having holes 40 to receive the outer ends of the set screws 15. Thus, the set screws 15, in addition to the functions already attributed to them, also function to locate and retain the plate 39 in proper position 60 against the arms or walls 10. Bars 41 have laterally extended arms 42 on one end adapted to engage in the notches 38. The opposite ends of the bars 41 extend through holes in the plate 39 and have slots 43 in their outer end portions 75 beyond the plate 39 adapted to receive curved

tapered levers 44. The plate 39 may also be formed with a flange 45 at each end to constitute a seat for the outer end portion of the adjacent lever 44. These curved levers 44 are extended through the slots 43 and seated against the seats 45. The inner ends of the levers 44 may then be struck by a hammer, or the like, and driven toward the plate 39, thereby forcibly withdrawing the ends of the return bends 7 from the sockets in which they are seated. Before the plate 39 is placed in position for use, the set screws 15 are screwed away from the shoulders 16 on the return bend, so that said set screws will not prevent the return bend from being partially withdrawn from the sockets in the housing members. After the return bend has been loosened, the plate 39 and cooperating parts may be removed and the return bend 7 may be taken off.

My invention may be varied otherwise than in the particulars mentioned, and I do not restrict myself unessentially.

I claim:

1. The combination with a return bend, of a housing therefor comprising a pair of sections, each being attached to one end of one tube of a pair of tubes, a portion on each of said sections extending toward the other section and each having a groove that is disaligned with the groove in the other section, a key attached to each of said sections and extending for sliding movements into the groove in the other section, a device attached to said keys limiting extent of spreading movement of said sections, elements attached to said keys and cooperating with said device to limit extent of relative longitudinal movements of said sections, and means preventing said elements from clampingly engaging said device.

2. The combination with a return bend, of a housing therefor comprising a pair of sections, each of which is attached to one end of one tube of a pair of tubes, a portion on each of said sections extending toward the other section and each of said sections having a groove disaligned from the groove in the other section, a key attached to each of said sections extending in the groove in the other section for longitudinal and lateral movements, and means mounted on said keys limiting extent of said longitudinal and lateral movements.

3. The combination with a return bend, of a housing therefor comprising a pair of sections, each of which is attached to one end of a pair of tubes, a portion on each of said sections extending toward the other section and each of said sections having a groove disaligned from the groove in the other section, a key attached to each of said sections extending in the groove in the other section for longitudinal and lateral movements, a plate between said housing sections having holes through which said keys extend, and means cooperating with said plate to limit extent of relative longitudinal and lateral movements of said housing sections.

4. The combination with a return bend, of a housing therefor comprising a pair of sections, each of which is attached to one end of a pair of tubes and each having a groove in the side thereof that is toward the other section, a key rigid with each section extending into said groove that is in the other section, a plate mounted between said sections and having holes through which said keys extend, means cooperating with said plate and said keys to limit relative longitudinal and lateral movements of said housing sections.

tive movement of said sections away from each other, and means attached to said keys and cooperating with said plate to limit relative longitudinal movements of said sections.

5. The combination with a return bend, of a housing therefor comprising a pair of sections, each of which is attached to one end of a pair of tubes and each having a groove in the side thereof that is toward the other section, a key rigid 10 with each section extending into said groove that is in the other section, a plate mounted between said sections and having holes through which

said keys extend, means cooperating with said plate and said keys to limit relative movement of said sections away from each other and to limit relative longitudinal movements of said sections, each of said sections having a tapered opening in its outer end beyond the end of the attached tube and telescoping on the adjacent end of the return bend, and clamping means supported by said sections for holding said return bend telescoped into said sections.

5
